CLAIM

The ornamental design for a carrying case for a portable telephone, as shown and described.

DESCRIPTION

FIG. 1 is a front perspective view of a carrying case for a portable telephone showing my new design;

FIG. 2 is a rear perspective view thereof;

FIG. 3 is a reduced front elevational view thereof;

FIG. 4 is a front perspective view of an alternate embodiment of the design shown in FIG. 1, and

FIG. 5 is a rear perspective view of FIG. 4.

FIG. 2

FIG. 5
